HOUSED OUTLET

Filed Nov. 18, 1930

UNITED STATES PATENT OFFICE

FREDERICK G. WEHMAN, OF WEST NYACK, NEW YORK, ASSIGNOR TO THE FIBRE CONDUIT COMPANY, OF ORANGEBURG, NEW YORK, A CORPORATION OF NEW YORK

HOUSED OUTLET

Application filed November 18, 1930. Serial No. 496,402.

This invention relates to electrical fittings for floor outlets. Floor outlets are made to extend a few inches above the floor, and in general are provided with an insulating fitting through which the electrical conductors pass.

A principal object of this invention is to provide a metallic protecting casing that will securely hold the insulating fitting in its proper relation to the upright tubular support, and protect it from injury.

Another object is to unite the metallic cover of the fitting to the tubular upright with a sleeve by engaging means that will act as a clamp holding the fitting securely onto the top of the upright.

A further object is to utilize the sleeve in connection with a bifurcated fitting cover to hold the two halves securely together and to the upright support.

A further object is to provide means for holding the fitting and its cover casing from turning when the sleeve is turned.

A further object is to provide accessibility to the binding posts of the fitting by a lowering of the sleeve without disturbing the relation of the other members.

Other objects will appear from the following description of an embodiment of the invention, in connection with the accompanying drawings, in which

Figure 1 is a vertical section and side view of a floor outlet.

Figure 2 is a section and side view on the line 2-2 of Figure 1.

Figure 3 is a perspective view of one half of the cover casing.

Figure 4 is a perspective view of the tubular riser or upright.

Figure 5 is an axial section of a modification.

Figure 6 is a section in side view, at right angles to the view of Figure 5.

A conduit as shown at 1 is laid under a floor 2, and has at various points uprights or risers 3 which are in the form of short nipples that are screwed or otherwise secured to the underfloor conduit 1, and rise for a distance of a few inches above the

floor. The riser 3 is preferably made with a collar or flange 4 at the upper end (see Figure 4). At 5 is shown a T-shaped insulating fitting which may be in the form shown in Figures 1 and 2, where the upper portions are provided with receptacles for terminal jacks, as shown at 6, with depending binding posts 7 that reach down into the hollow lower legs 8 of the fitting, or as shown in Figure 5, the fitting 5a may be a plain T with vertical and horizontal openings through which wires may be led from the underfloor conduit out into the open. These fittings are preferably made in two halves split on a vertical median plane, alignment being secured by having their contacting surfaces provided with corresponding dowels and sockets. At 9 are shown the two halves of the vertically-divided T-shaped metallic housing or casing. These housing parts are shaped as shown in Figure 3, and are characterized by an interior horizontal wall that closely fits the exterior contour of the insulating fitting. While the lower part 10 is formed with a screw-thread on its outer periphery which is adapted to engage with an internal screw-thread on a metallic sleeve 11, which has at 11a an inturned flange, to engage beneath the flange 4 of riser 3, these flanges forming interlocking means between the sleeve and housing. The lower end of the fitting rests upon the upper end of the riser, and is drawn into close contact therewith by the engagement of flanges 4 and 11a on the tightening of the screw-threads on 10 and 11. To prevent the fitting from turning when the sleeve 11 is turned, interlocking means are provided between the fitting and the riser, which, in the example shown, takes the form of projections 12 on the fitting, and slots 13 on the riser. A screw 14 in the upper end of the housing 9 may be used to hold the two parts of the housing together, and the half-housings are further clamped together by the collar 11 when screwed into position. The collar 11 is made to screw up against a shoulder on the lower part of the housing 9 when the parts are in clamped together po-

100

sition, so that a metallic casing is provided having a rigid relation with the conduit system and with the fitting, and which entirely covers and armors the fitting, with the exception of the exposed sides which are made flush with the ends of the housing, so that there is no possibility of the fitting being injured. The lower ends of the fitting that has the binding posts 7, are provided with openings 15 through which access may be had to the binding posts for the making of electrical connections when the sleeve 11 is lowered. To allow full vertical amplitude to the openings 15, they may extend above the lower edge of the housing as shown, the lower screw-threaded end of the housing being notched to expose the full height of said openings. It will be noticed that the fitting is in its final position when such connections are made, the subsequent screwing on of the sleeve not affecting in any way the position of the fitting.

While in the embodiment shown, screw-threads and collars or flanges have been mentioned as means of engaging the collar 11 with the casing 9 and the riser 3, it is to be understood that other well-known equivalents may be used instead.

I claim:

1. An outlet floor riser comprising in combination, a tubular supporting member, a sleeve slidably mounted on the supporting member, interlocking means between the sleeve and the supporting member, a metallic casing divided vertically into two halves and having lower portions adapted to engage the sleeve and be held together thereby, and an insulating fitting between the two halves of the said casing and clamped in position by the engaging of the lower portion of the casing with the sleeve.

2. An outlet floor riser comprising in combination, a tubular supporting member, an internal threaded sleeve slidably mounted on the supporting member, interlocking means between the sleeve and the supporting member, a metallic casing divided vertically into two halves and having screw-threaded lower portions adapted to engage the screw-threads of the sleeve and be held together thereby, and an insulating fitting between the two halves of the said casing and held in position by the tightening of the screw sleeve on the screw extensions of the casing.

3. An outlet floor riser comprising in combination, a metallic tubular supporting member having a collar at its upper edge, an interiorly screw-threaded sleeve slidably mounted on the supporting member having a collar engaging the collar on the said supporting member, a metallic casing divided vertically into two halves and having screw-threaded lower portions adapted to engage the screw-thread of the sleeve and be held

together thereby, and an insulating fitting held between the two halves of the said casing and adapted to be clamped against the upper edge of the said support by the tightening of the screw sleeve on the screw extensions of the casing. 70

4. An outlet floor riser comprising in combination, a tubular supporting member, a sleeve slidably mounted on the supporting member, interlocking means between the sleeve and the supporting member, a metallic casing divided vertically into two halves and having lower portions adapted to engage the sleeve and be held together thereby, and an insulating fitting between the two halves of the said casing and held in position by the engaging of the lower portion of the casing with the sleeve, the said fitting and the said supporting member interlocking to prevent the turning of the fitting relative to 85 the support.

5. An outlet riser comprising in combination, a metallic tubular support, a sleeve slidably mounted on the support, a vertically divided metallic casing, a T fitting of insulating material clamped between the two halves of the casing and extending down to the support, means on the sleeve cooperating with means on the casing and on the support to clamp the fitting between the casing 95 and the support.

6. An outlet riser comprising in combination, a metallic tubular support, a sleeve slidably mounted on the support, a vertically divided metallic casing, a T fitting of insulating material clamped between the two halves of the casing and extending down to the support, means on the sleeve cooperating with means on the casing and on the support to clamp the fitting between the casing 100 and the support, with means on the upper end of the support and lower end of the fitting for preventing the turning of the fitting.

7. An outlet riser comprising in combination, a metallic tubular support, a sleeve slidably mounted on the support, a vertically divided metallic casing, a T fitting of insulating material clamped between the two halves of the casing and extending down to the support, means on the sleeve cooperating with means on the casing and on the support to clamp the fitting between the casing and the support, the lower end of the fitting having binding posts and side openings in the zone of the sleeve for access to the binding posts. 115

FREDERICK G. WEHMAN.
